UNITED STATES PATENT OFFICE.

ERNEST FLAGG, OF NEW YORK, N. Y.

OUTSIDE WINDOW SHADE.

Application filed October 14, 1921. Serial No. 507,603.

To all whom it may concern:

Be it known that I, ERNEST FLAGG, a citizen of the United States, and a resident of the city of New York, borough of Richmond, in the county of Richmond and State of New York, have invented a new and Improved Outside Window Shade, of which the following is a full, clear, and exact description.

10 Inside shades are by many considered undesirable and not beautiful and, also, they are liable to soil curtains and interfere with casement windows. If made of suitable material and placed outside the window, a shade is much less objectionable, but that involves certain difficulties which it is the object of my invention to overcome.

In order to operate an outside shade from the inside of the window, obviously a cord 20 must pass through the frame or through the sash. If the cord is passed transversely through the frame, then it is necessary to build a cornice or cover to afford protection for the roller against the weather. If the cord is passed through the sash, the roller may be placed under the head of the frame and so protected from the weather, but if this is done a difficulty arises when the sash is opened, for in doing so the cord 30 is pulled, and if the shade is rolled tightly the cord is likely to be broken. To overcome these disadvantages, I carry the cord upwardly into the frame head through a hole or sinking at the under side, with guide 35 means for the cord, and I form a transverse passage from the sinking to the inside of the frame.

The nature of the invention and its distinctive features and advantages will more 40 clearly appear as the description proceeds.

Reference is to be had to the accompanying drawings forming part of this specification, it being understood that the drawings are merely illustrative of one example of the 45 invention.

Figure 1 is an elevation of a window embodying my outside shade assemblage.

Figure 2 is a transverse vertical section on an enlarged scale, in a plane indicated 50 by the line 2-2 of Figure 1.

Figure 3 is a transverse section on a still larger scale, as indicated by the line 3-3 of Figure 4, and

Figure 4 is a vertical section at right angles to Figure 3, as indicated by the line 55 4-4.

In carrying out my invention in accordance with the illustrated example, a shade roller 10 is mounted on brackets 11 in the plane of the window frame 12 outside the 60 plane of the sash A, hinged as at a. A shade 13, of suitable material, to withstand the weather, winds on the roller 10 and the projecting ends of its stick 13^a have guided movement on vertical rods 14 secured to the 65 opposite sides of the window frame and here shown as secured at the upper and lower ends by pins 15 to the window jambs.

An operating cord 16 is provided for the roller 10 and winds on an enlargement or 70 spool portion 10^a of the roller 10. From the roller, the sash cord 16 extends upwardly into the head 17 of the frame, said head being formed with a sinking cut 18 therein at the underside adjacent to one end, 75 there being a suitable guide for the cord, the guide being here shown as consisting of a screw eye 19. A transverse passage 20 is formed in the head 17 and leads from the sinking cut 18 to the inside of the 80 frame, the head 17 having a guard 21 in the form of a disk or plate with a hub 22, through which the cord 16 may extend. Thus, the cord is guided and protected by the screw eye 19 or the equivalent and the 85 guide element 21 to prevent wear of the cord.

At the cord zone 10^a, the roller 10 is provided with flanges 23, thereby providing a spool for the cord on the roller 10. The cord 16 hangs at the inside of the frame as 90 at 16^b and is provided with a tassel 16^b or other hand pull.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim:

1. A window and shade assemblage comprising a window frame having a head formed with a sinking cut in the under side and with a passage extending forwardly from said cut through the head to the inner side of the window, a shade roller mounted in a frame beneath the head thereof outside of the plane of the sash and an operating cord winding on the roller for the raising and lowering of the shade, said cord 105
- 110

extending upwardly into said cut and through said passage to the inner side of the window.

2. A window and shade assemblage comprising a window frame having a head formed with a sinking cut in the under side and with a passage extending forwardly from said cut through the head to the inner side of the window, a shade roller 10 mounted in a frame beneath the head thereof outside of the plane of the sash and an operating cord winding on the roller for the raising and lowering of the shade, said cord extending upwardly into said cut and 15 through said passage to the inner side of the window, together with vertical guides on

the window frame at the sides, the shade stick having sliding engagement with said guide.

3. A window frame adapted to mount a shade roller outside of the plane of the sash and having a head formed with a transverse cord passage extending from the inner side of the frame and terminating between the outside of the frame and the 25 plane of the sash, said head affording a vertical passage for a cord to the outer end of the said first passage, and guides for the cord at the inner end of said second mentioned passage adjacent to the outer end 30 of the first passage.

ERNEST FLAGG.
